Oliver P. Myers

By Smith & Bowles, Mfg.

UNITED STATES PATENT OFFICE.

OLIVER PERRY MYERS, OF SAN FRANCISCO, CALIFORNIA.

DENTAL-MOUTH-MIRROR SUPPORT.

SPECIFICATION forming part of Letters Patent No. 552,693, dated January 7, 1896.

Application filed February 24, 1894. Serial No. 501,407. (No model.)

To all whom it may concern:

Be it known that I, OLIVER PERRY MYERS, a citizen of the United States, residing in the city and county of San Francisco and State 5 of California, have invented certain new and useful Improvements in Adjustable Supports for Dental Mirrors and other Appliances, of which the following is a specification.

This invention relates to appliances for 10 holding dental mirrors and other tools of the dentist in working or acting position at the operating-chair; and the invention consists in the described construction and combination of parts producing an improved device 15 or attachment that is capable of being fixed in position for use on most any of the present styles or constructions of dentists' operating-chairs, and that possesses besides such qualities of universal adjustment in its parts or 20 members that it will hold in a steady and reliable manner a mirror or other appliance in any position for use without interfering with the operator at the chair.

The following description explains the nature of my said improvements and the manner in which I have constructed and combined the same for operation and use, reference being had therein to the accompanying drawings, forming part of this specification.

30 In the said drawings, Figure 1 is a view in perspective of the complete device with a dental mirror fixed in the socket on the end. Fig. 2 is a view on an enlarged scale of two members or sections and the joint that unites them. In the lower part of this figure the upper portion of the socket by which the holder is fixed to the chair is shown in section. Fig. 3 is a detail view, partly in section and on an enlarged scale, of the outer member or section 35 and the adjustable holder for the mirror or other appliance on the outer end. Fig. 4 is a perspective view of one of a set of clamps by which the tubular socket of the device is secured to the frame of the dental chair. Fig. 45 5 is a detail view, mostly in section, of the adjustable socket and holder for the mirror or other part on the end of the device. Fig. 6 is a view in perspective of a clamp and an adjustable socket of another construction for 50 attaching my device to styles of dental chairs to which the form of clamp shown in Figs. 1 and 4 cannot be applied. Fig. 7 is a view in

detail of the socket portion of the clamp, Fig. 6.

Referring by letter to the parts in these figures of the drawings, A represents a tubular socket open at both ends, with the upper end split longitudinally, as indicated at a^x and A' , a clamp fitted around such split portion to contract it at the end of the socket. This 55 piece A' is a split ferrule with ears a^2 and a thumb-screw A^3 . In one ear is a threaded hole for the screw, and in the other ear, against which the head of the screw works, a smooth 60 hole.

65 B represents a rod fitted to slide longitudinally and also rotatable or movable axially in the socket A, in which it is clamped and held at any point by tightening the screw A^3 . When the socket A is fixed to the chair-frame 70 the part B before mentioned can be moved and adjusted longitudinally and also axially by turning it within the socket.

75 C indicates a tubular rod and C' a solid cylindrical rod forming a telescopic or extensible member or part of the section. These two last-mentioned parts are connected by a hinge-joint composed of a leaf or knuckle b^x on the end of the part B and a pair of knuckles $b^8 b^9$ on the adjacent end of the part. 80 C^x is a screw-bolt set through the eyes or holes in the knuckles before mentioned, and C^2 is a nut on the same. By these parts the hinge is tightened and any loose movement is taken up. By tightening the screw also the hinge 85 is converted into a fixed or rigid joint.

90 The part C is tubular for the whole or greater portion of its length, and the part C' being fitted to slide smoothly in it may be a solid rod. C^2 is a tapering sleeve screw-threaded internally and fitted to work on the tube C and clamp the two parts, the end of the tube C being split longitudinally and the rod C' threaded on the external surface to take the sleeve C^2 . Sufficient degree of friction is produced by this sleeve to prevent the part C' from turning in that tubular piece. 95 The next member of the device is similarly formed of the tubular section D and the rod D' movable longitudinally and also capable of 100 being turned within the tube. The end of the tubular part D is screw-threaded and split and fitted with a threaded sleeve C^2 for a clamp, acting in the same manner as the

means and clamp on the section C C'. The section D D' is united to the section C C' by a hinge-joint in the same manner as the section C C' is connected to the rod B, and the same construction is followed in the case of this second joint. On the end of this last-described section or member of the device is an adjustable holder with a socket and clamp to receive and securely hold the mirror or other appliance. This part is composed of a tubular socket E open at both ends and attached to the outer end of the member D' by a hinge-joint. Into this socket-piece E is set a tubular piece F having one end split and fitted with a threaded sleeve F², and a cylindrical rod or spindle G is fitted in the piece F to slide longitudinally and also capable of being rotated in the aforesaid part F. One end of this spindle is provided with a milled head g' for turning it, and in the opposite end a socket g² is formed to receive a tang or piece on the mirror or other appliance, which is inserted in the socket in attaching it to this holder. The sleeve E is attached to the extensible part D D' by a hinge d³ d³, the pin d³ of which is formed of a screw, so that any degree of friction can be produced at this joint by tightening or loosening the screw. The clamp F² on the end of the tube F is constructed like the clamp on the sections C C' and D D'.

In some cases I find it better to increase the number of telescopic or adjustable sections or members of this device, and in some styles or "makes" of dental chairs an additional extensible or telescopic sections on the end of the section D D' will be found to work to advantage. There are some styles of chairs, however, on which the holder constructed with the upright section A and the two horizontally-disposed sections C C' D D' will work or operate satisfactorily. As thus constructed and put together the sections C C' and D D' are extensible in length at the joints and the sliding members C' D' are rotatable or capable of being turned axially within the tubular members. In addition to these movements the two sections are movable in angular directions with respect to each other by virtue of the hinge-joints, and thereby such universality of adjustment is allowed that the mirror or other fixed piece on the outer end of the device can be set in any position and in all possible positions of use without obstructing the proper use of the instruments and tools while operating on a patient, and will be held firmly and steadily by the holder in any such position of adjustment without danger of dropping or moving out of place.

By securing the socket A for the lower member B of the upright section to the frame of the operating-chair by means of a clamp or strap secured to the frame the entire holder can be removed and replaced as often as required for use by simply loosening the clamp A' and drawing the rod B out of the socket-

piece A. Ordinarily the device need not be removed from the chair, but it can be turned back away from the front, so that it extends 70 directly behind the chair toward the rear, such position out of use being obtained by turning the rod B around within the socket A or by turning the two sections C C' D D' at the hinge-joints, so that they stand perpendicular upward and in line with the sections A A, or, in another way, by setting the two sections C C' D D' in a straight line and then turning them horizontally backward or to the rear at the hinge-joint between B and C. 80 Additional scope and also readiness of adjustment of the mirror or appliance carried by the holder is afforded by the peculiar construction and arrangement of the socket and spindle F C before described. It should be 85 noticed that the spindle C is fitted to move longitudinally within the tubular member F and is also rotatable or can be turned to change the angle of the mirror, and in addition to these adjustments the socket F, which 90 connects the tubular member D to the end of the outer section D', is adjustable in different angles by virtue of the hinge d³ d³, the direction of which can be changed by rotating the member D' in the tubular member D of that 95 section.

The clamps H H' represented in Figs. 1 and 4 form a convenient and efficient means of securing the socket A' on the back of the frame of a dental chair where the block or 100 frame of the head-rest is fitted to slide between upright ribs or guides on the chair-frame, and these clamps are shaped to slip over and fit tightly upon the guides. The upper clamp H is secured to the socket by a 105 screw h² entered from the outside and taking into the clamp, while the lower clamp H' embraces the socket and holds it against the frame. A clamp of this character may be secured to the frame of an operating-chair also 110 by drilling and tapping holes in the frame for screws that are inserted through the clamps.

Figs. 6 and 7 represent a construction of socket which I have used to good advantage on a dental chair on which the guides for the 115 head-rest are formed to receive a dovetail block or piece on the sliding head-rest and in which the head-rest sets back at such an inclination from the perpendicular that it is necessary to hold the upright member B of 120 my device at a greater or less degree of inclination to one side or the other away from the perpendicular. This style of clamp is formed of the bar H³, having the chamfered blocks h⁴ h⁴ fixed to its front face to set into 125 the dovetailed way or recess in the guides of the head-rest just under that part and with an eye h⁵ near the outer end, in which is fitted the screw-threaded shank H⁷ of a socket-piece H⁶ H⁶. The part H⁶ is solid with or is rigid 130 on the screw H⁷ and has a tubular aperture h¹⁰ through it to receive the rod B. The other part H⁹ is a separate piece fitting loosely on a shouldered portion of reduced diameter and

also partly cut away to fit around rod B when the same is in the socket. This part forms a clamp to bind the rod B when the shank H⁷ is set through the hole in the bar H⁴ and is drawn up by the butterfly-nut H¹². By unscrewing this nut the socket can be turned on the bar A⁴ to set the rod B at different angles as the adjustment of the device may call for during work.

Having thus described my invention, what I claim as new, and desire to secure by Letters Patent, is—

A holder for dental-mirrors and other appliances on a dentist's operating chair consisting of a fixed socket on the chair, a standing rod adjustable both axially and longitudinally in such socket, two or more extensible

sections each composed of two telescopic members adjustable both axially and longitudinally on each other, a clamping means at the joint between the two members, a hinge-joint uniting said sections and provided with means of tightening the same to produce a rigid joint after angular adjustment of the sections, a tubular socket hinged on the end of the outer section and means for fixing in such socket the shank of a mirror or other appliance, combined for operation as set forth.

In testimony that I claim the foregoing I have hereunto set my hand and seal.
